UNITED STATES PATENT OFFICE

138,061

DESIGN FOR A MILKING DEVICE

Louis J. Belanger, Graniteville, Vt.

Application January 18, 1944, Serial No. 112,255

Term of patent 14 years

(Cl. D23—1)

To all whom it may concern:

Be it known that I, Louis J. Belanger, a citizen of the United States, residing at Graniteville, in the county of Washington and State of Vermont, have invented a new, original, and ornamental Design for a Milking Device, of which the following is a specification, reference being had to the accompanying drawing, forming part thereof.

Fig. 1 is a front view of the milking device showing my new design;

Figs. 2 and 3 are transverse sectional views, taken along the lines 2—2 and 3—3 respectively in Fig. 1;

Fig. 4 is a longitudinal sectional view, taken along the line 4—4 in Fig. 1; and

Fig. 5 is a left-hand side elevation, looking in the direction of the arrow 5 in Fig. 1.

I claim:

The ornamental design for a milking device, as shown.

LOUIS J. BELANGER.
